SLIDING DOOR STRUCTURE

Harold P. Harle, Louisville, Ky., assignor to General Electric Company, a corporation of New York
Filed Dec. 28, 1961, Ser. No. 162,733
1 Claim. (Cl. 20—19)

The present invention relates to a sliding door structure and is more particularly concerned with an improved closure structure comprising a pair of sliding doors for closing the access opening to a refrigerator cabinet or the like.

It is an object of the present invention to provide means for closing the access opening to a cabinet or the like comprising a pair of sliding doors which are positioned in the same plane and in side-by-side relationship when in their closed position and improved means for guiding the movement of either one of the doors in its travel between its closed position and an open position in which it is positioned in front of the other of the doors.

Another object of the invention is to provide an improved means for mounting a pair of sliding doors comprising pins carried by the doors, interconnected grooves for slidably receiving the pins controlling the opening and closing movement of either of the doors and guide means associated with the interconnected grooves for directing the travel of the pins during opening or closing movement of one or the other of the doors.

Further objects and advantages of the present invention will become apparent from the following description and the features of novelty which characterize the invention will be pointed out with particularity in the claim annexed to and forming part of this specification.

In carrying out the objects of the present invention there are provided a pair of sliding doors for closing the access opening to a cabinet or the like and means for supporting the doors with reference to the access opening for movement of either door between a closed position in which both doors are in the same plane and in side-by-side relationship and an open position in which the open door is in front of and parallel to the other. The support means which guides or directs the movement of either door between its closed and open positions comprises track plates mounted above and below the access opening and including interconnected track grooves in which pins carried by the doors are adapted to slide. Each track plate includes a main groove extending substantially the width of the access opening and generally parallel to the cabinet face portion defining that opening and terminating at its opposite ends in rearwardly inclined end portions. On each side of the mid-point of the main track groove, that is, on each side of the point at which the inner edges of the doors meet when in their closed positions, there is provided a rearwardly extending relatively short groove communicating with the main groove. The pins carried by each door are adapted to ride in appropriate portions of the main groove or in one or the other of the rearwardly extending grooves for guiding and supporting the door in its various positions. During movement of either door between its closed and opened positions, certain of the pins carried by that door are arranged to move into or out of one of the rearwardly extending grooves and guide means are provided for the purpose of guiding or directing the movement of such pins.

Another aspect of the present invention is the provision of a sliding door structure including magnetic means for drawing the doors to their closed positions and for maintaining the doors in sealing engagement with a cabinet face portion.

For a better understanding of the invention, reference

2

may be had to the following description taken in conjunction with the accompanying drawing in which:

FIGURE 1 is a front view of a portion of a refrigerator cabinet including the sliding door structure of the present invention;

FIGURE 2 is an enlarged sectional view taken generally along the line 2—2 of FIGURE 1; and

FIGURE 3 is a sectional view taken generally along the line 3—3 of FIGURE 2.

- 10 While the sliding door structure of the present invention is applicable to the closing of the access openings to various cabinets and the like, it will be particularly described in connection with a preferred embodiment thereof particularly designed for closing an access opening to a refrigerator cabinet which involves the additional problem of sealing the space between the doors and the face portion of the cabinet when the doors are closed.

With reference to the drawing, there is shown in FIGURE 1 a portion of a refrigerator cabinet including an upper storage compartment of the general shape of a kitchen wall cabinet and closed by means of a pair of doors 1 and a lower storage compartment closed by means of a pair of doors 2 and having the general shape of a counter type of kitchen cabinet. The top surface 3 of this lower portion of the cabinet forms a counter or work surface corresponding to the usual counter or work surface in an ordinary kitchen cabinet arrangement. Positioned between the upper and lower storage compartments and having a face portion recessed with reference to the face portion of the upper storage compartment is an intermediate compartment 4 having an access opening 5 which is closed by means of a pair of sliding doors 6 and 7, which doors and their mounting structure form the subject matter of the present invention.

35 In order that movement of the doors 6 and 7 will not interfere with normal use of the work surface 3, the sliding doors 6 and 7 are arranged so that either one can be moved horizontally from its closed position in which both doors are in side-by-side relationship and in the same vertical plane to an open position in which one of the doors is in front of the other door.

As is more clearly shown in FIGURE 3 of the drawing the doors 6 and 7 are mounted in the recessed area between the bottom wall 10 of the upper storage compartment and the work surface 3 forming the top wall of the lower compartment. In accordance with the usual refrigerator cabinet practice the doors are of double wall construction including an outer panel 11, and an inner panel 12, the space between these panels being filled with suitable heat insulating material 14. The doors are of a size such that their peripheral edges overlie or overlap the face portion 15 of the cabinet surrounding the access opening 5 and a suitable gasket 17 is provided on each of the doors for sealing the space between the doors and the cabinet face portion 15.

In the illustrated embodiment of the invention, the access opening 5 is divided into two sections by a vertical mullion 16 adapted to bridge the space between the doors 6 and 7 when in their closed position. However, it is to be understood that the invention is not limited to the use of the mullion 16 since this space can be sealed by means of a gasket or gaskets carried by the opposed inner edges 18 and 19 of the respective doors 6 and 7.

65 For mounting the doors for horizontal sliding movement of either one of them between a closed position in which both of the doors are in the same plane and in sealing engagement with the face portion of the cabinet surrounding the access opening 4 and an open position in which the open door is in front of the closed door, there is provided a mounting means in the form of track plates 20 and 20a respectively secured to the cabinet above and

below the access opening 4. Each plate is provided with track grooves adapted to receive pins carried by the doors 6 and 7, the grooves and pins being cooperatively arranged to position the doors in their closed and open positions and to direct the movement of the doors between these limiting positions.

Insofar as the groove pattern is concerned, the plates 20 and 20a are of the same construction. As illustrated in FIGURE 2 of the drawing showing the upper plate 20, the face, or in other words the bottom surface of this plate, is provided with a main groove 21 the major portion 22 of which extends substantially the full length of the plate in parallel relationship with the face portion 15 of the cabinet surrounding the access opening 5 to the compartment 4. The opposite end portions 23 of the main groove 21 slope rearwardly towards the face of the cabinet and terminate in relatively short rearwardly extending portions 24. A pair of spaced rearwardly extending grooves 26 and 27 are provided on opposite sides of the center line of the plate or in other words on opposite sides of the point at which the inner edges 18 and 19 of the respective doors meet when in their closed positions. These rearwardly extending grooves 26 and 27 communicate with or are connected to the main portion 22 of the groove 21 through curved sections 28 and 29 which curve inwardly or towards one another as illustrated in FIGURE 2.

Inner and outer pins carried on the upper and lower edges of the doors 6 and 7 and adjacent the ends thereof are adapted for sliding movement in the grooves provided in the plates 20 and 21 and together with these grooves provide the sole means for supporting the sliding doors relative to the cabinet face. Specifically the door 6 is provided with outer pins 31 in the top and bottom edges thereof and adjacent the outer edge 32 of the door 6 and inner pins 33 similarly positioned in the upper and lower edges of the door 6 adjacent the inner edge 18 thereof. Outer pins 35 and inner pins 36 are similarly provided adjacent the outer edge 38 and the inner edge 19 of the door 7.

The outer pins 31 and 35 are so arranged that they rest in the extreme ends 24 of the main groove 21 when the doors are in sealing or closing relationship with reference to the access opening 5. Also when the doors 6 and 7 are in their closed positions, the inner pins 33 and 36 are respectively positioned in the rearward ends of the rearwardly extending grooves 26 and 27. These positions of the pins when the door is closed are illustrated with reference to door 6 in FIGURE 2 of the drawing.

In order that either one of the doors 6 and 7 can be moved to an open position in front of the other door, the grooves in the track plates 20 and 21 are so designed as to guide the movement of the door being opened first forwardly in order that it will clear the closed door and then horizontally to an open position in which half of the access opening 5 is unobstructed. When either door is in its open position, the pins carried thereby are essentially riding in the straight portions 22 of the main groove 21 and these portions 22 are spaced from the front portion 15 of the cabinet or in other words from the front surface of the door which remains closed a distance sufficient so that the door moving to its open position will clear the closed door.

With reference to FIGURE 2 of the drawing, the door 7 is shown at one point in its travel to an open position. It will be noted that the inner pin 36 has moved forwardly and out of the groove 27 and into the main groove 21. Movement of the door to this position is accomplished by grasping the handle 37 provided adjacent the inner edge of the door and pulling the door forwardly. When the inner edge 19 of the door 7 has cleared the inner edge 18 of the closed door 6, that is when the pin 36 has reached and is riding in the main groove 21, the door 7 is free to be moved horizontally, that is to the left as viewed in FIGURE 2, to a fully open position in front of the closed door 6. The sloping outer edge portion 23 of the

main groove is designed to guide the outer edge 38 of the door 7 forwardly during the initial movement of the door horizontally to separate the gasket 17 from the face of the cabinet and thereby avoid gasket rub during opening of the door.

To facilitate the opening and closing travel of the doors, there is provided in accordance with the present invention guides 40 and 41. These guides each include surface portions which in cooperation with the groove pattern provided in the plates will facilitate movement of a door between an opened and a closed position or in the reverse direction. The guides 40 and 41 may be provided on either one or both of the plates 20 and 21. In the illustrated embodiment of the invention, these guides are provided only on the upper plate 20 and as shown in FIGURE 2 of the drawing they are respectively pivotally mounted by means of pivot pins 42 and 43 at points outwardly from the respective grooves 26 and 27 and rearwardly from the main or straight portion 22 of the groove 21. Both of the guides 40 and 41 are spring biased to a forward position by means of a spring 45 and in this position an angular, or preferably curved, surface portion 46 extends across the main groove 21 and in effect forms a continuation or part of outer edge of the curved portion 29 of groove 27. The purpose of this curved or angular portion 46 is to direct the travel of the inner pins as for example inner pin 36 on the door 7 during movement of that door between its limiting positions. When the door is being moved to its open position and the pin 36 is travelling forwardly in the groove 27, contact of the pin with the section 46 tends to move or throw the door in a horizontal direction even though the forces being applied to the door by pulling on handle 37 are directed essentially in a forward direction. The result is that there is a smooth transition between the outward pull required to move the door 7 forwardly in order to clear the inner edge of the closed door 6 and the horizontal pressure which is then applied to move the door horizontally to a position in front of the closed door 6.

During closing of the open door as for example during closing of the door 7 the portion 46 provides a similar function but in reverse. Contact of the pin 36 with the portion 46 which is closing the remaining portion of the guide 21 to the pin 36 as it moves to the left as illustrated in FIGURE 2 in effect translates the horizontal pressure being applied to the door to a rearwardly directed force so that the door easily moves rearwardly to its closed position.

Each of the guides 40 and 41 also includes a camming surface 48 which is adapted to be contacted by an inner pin as the door carrying that pin moves to its fully closed position and thereby pivots the guide to the position occupied by the guide 40 in FIGURE 2 of the drawing. This movement of the guides removes the surface portion 46 from the groove 21 and also places a straight surface portion 49 of the guide in a position to close or block one of the rearwardly extending grooves into which the pin has moved. For example, pin 33 by engaging guide 40 pivots that guide to the position shown so that groove 26 is blocked so that inner pin 36 carried by door 7 cannot enter groove 26 during its travel in groove 21. In other words, the straight portion 49 of each guide forms a continuation of the rear edge of the groove 21 so that the pin 36 on the door 7 cannot enter the groove 26 during opening and closing movement of the door 7 and pin 33 cannot enter groove 27 during movement of door 6. Since each of the guides are biased to its forward position by the spring 45, it will be held in its first or forward position whenever the door controlling the action of that guide is moved forwardly so that the surface 46 can perform its switching function.

In accordance with another aspect of the present invention, a preferred latching means for holding each of the doors 6 and 7 in their closed positions is designed not only to perform a latching function but also to pull or bias

either door to its closed position as the inner pins carried thereby travel into one of the rearwardly extending grooves 26 and 27. In the illustrated embodiment of the invention, this action is obtained by employing a gasket 17 which includes a permanent magnet material 50 carried in the face portion of the gasket and by forming the face portion 15 of the cabinet being engaged by the gasket face portion of a magnetically attractive material such as steel or the like. The magnetic gasket may extend about the four sides of the door as in the illustrated embodiment of the invention or at least along the upper and bottom edges of the door in the event the mullion 16 is omitted. The attraction between the magnets 50 and the face portion 15 of the cabinet will cause the magnetic gasket to come into sealing engagement with the cabinet along its entire length. During closing movement of either of the doors, the first portion of the magnetic gasket which comes into contact with the face portion of the cabinet is the vertically extending section 51 on the outer edge 38 and the adjacent portions of the gasket on the top and bottom edges of the door. When this portion of the door structure is attracted into engagement with the cabinet face portion, the intermediate portions of the magnetic gasket extending along the top and bottom edges of the door are progressively closer to the face portion of the cabinet adjacent the outer edges of the door even though the inner edge for example edge 19 of the door 7 is still spaced a substantial distance from the cabinet face. There is thus a tendency for the gasket 50 and hence the door to which it is attached to be pulled inwardly by the magnetic attraction between the magnets and the face portion of the cabinet. These attractive forces progressively come into action from the outer to the inner edge of the door ultimately causing the entire door structure to pull inwardly to its closed position.

While there has been shown and described a specific embodiment of the present invention it is to be understood that the invention is not limited thereto and is intended by the appended claim to cover all modifications coming within the true spirit and scope of the invention.

What I claim as new and desire to secure by Letters Patent of the United States is:

In a cabinet having a magnetic face portion defining an access opening to said cabinet; a pair of sliding doors for closing said access opening, means for mounting said doors for horizontal sliding movement of either one of said doors between a closed position in which both of said doors are in the same plane with their inner edges in side-by-side relationship and their upper and lower edges overlapping said cabinet face portion and an open position in which one of said doors overlies the other of said doors in parallel relationship therewith, said mounting means comprising track plates respectively mounted above and below said access opening and having track grooves therein and inner and outer pins carried by the upper and lower edges of said doors for sliding movement in said grooves, each of said track plates including a main track groove having its major portion parallel to said cabinet face portion and its opposite ends inclined rearwardly toward said face portion and terminating in rearwardly extending end portions and a pair of spaced rearwardly extending grooves on opposite sides of the point at which the inner edges of said doors meet when in the closed position for receiving said inner pins when said doors are closed, and a magnetic gasket mounted adjacent the upper and lower edges of said doors for engaging said cabinet face portion when said doors are closed, said magnetic gasket progressively attracting said doors to their closed positions when said outer pins enter said rearwardly extending end portions.
